UNITED STATES PATENT OFFICE.

BERT A. SEBRING, OF ARVADA, COLORADO.

MOTOR-VEHICLE SIGNALING DEVICE.

1,268,287.

Specification of Letters Patent. Patented June 4, 1918.

Application filed June 21, 1915. Serial No. 35,347.

To all whom it may concern:

Be it known that I, BERT A. SEBRING, a citizen of the United States, and a resident of Arvada, and State of Colorado, have invented a certain new and useful Improvement in Motor-Vehicle Signaling Devices, of which the following is a full, clear, and exact description.

This invention is an improvement in signaling devices for motor vehicles and its primary object is to provide a simple, convenient and compact device for indicating to other drivers and to traffic officers the direction which it is intended to take at an approaching corner. More particularly the invention contemplates the use of compressed air as an actuating medium and means whereby the device will display the desired signal and then automatically, after any desired predetermined expiration of time, return to neutral. Further and more detailed objects and advantages of my invention will later appear in the specification.

25 In the single sheet of drawings accompanying this application and forming a part hereof—

Figure 1 is a detached perspective view showing the indicating and actuating parts removed from their casing;

Fig. 2 is a diagrammatic elevation showing the indicator, the source of power therefor and the situation of the means for controlling the application of power; and

35 Fig. 3 is an enlarged detail view of the motive fluid controlling valve.

Referring to the drawings, 4 is the indicator casing which has a bracket 5 by which it may be attached to any desired part of a motor vehicle. In one side of the casing there is an elongated transparent portion 6 through which the drum 7 (shown in Fig. 1) may be viewed. This drum is revolvably mounted on trunnions 8, 9, bearing in brackets 10 carried by the casing 4. The drum 7 is preferably provided with at least one blank side 11 and with two other sides bearing oppositely pointing arrows marked respectively Right and Left disposed as shown with reference to the side 11. The trunnion 9 carries fixed thereon the pinion 12 which is in position to be engaged by the rack 13 which is held in engagement with the pinion by bearing on the foot of the bracket 10. The rack 13 is carried by the parallel bent ends of the piston rod 14 which

is adapted to be reciprocated by the double acting piston 15 which works each way in the cylinder 16 against the action of a compression spring 17. Pipes 18, 19, supply motive fluid to the opposite ends of the cylinder 16. These pipes lead from a valve 20 to which the motive fluid is admitted by the feed pipe 21 from the reservoir 22 which is charged from any suitable source 23.

In Fig. 3 the valve 20 is shown in plan on enlarged scale. The valve stem 24 is adapted to be turned by the handle 25 in either direction from neutral (in which position it is shown) and thus supply air to pipe 18 or 19 as desired. When turned in either direction the handle 25 will flex the corresponding spring 26 which will tend to return the valve to neutral as soon as pressure is released from the handle 25.

At one end of the drum (the left end being selected in the drawing to avoid confusion of lines) electrical contacts 27, 28, connected to the leads 29 of a lighting circuit are provided. On the same end of the drum 80 a contact bar 30 in position to engage both the contacts 27, 28 in either indicating position of the drum is provided, and a light 31 is mounted in the casing in position to illuminate the indicating mechanism and is 85 wired in series with the contacts 27, 28.

Operation.

Assuming that the parts are in neutral position, as shown in Fig. 1, if the valve handle 25 be turned toward the left to the position shown in full lines in Fig. 2, air will be admitted through the pipe 18 to the right hand side of the piston 15 which will then be forced to the left hand end of the cylinder 16—carrying with it the piston rod 14 and the rack 13. The latter will rotate the pinion 12 which will turn the trunnion 9 and the drum 7 in a clockwise direction, thus displaying the side of the drum marked 100 Left opposite the transparent portion 6 of the casing 4, as indicated in Fig. 2. The passing of a sufficient amount of air through the valve 20 to work the piston will take but an instant and as soon as the driver releases the valve handle 25 the spring 26 which has been flexed will return the valve 20 to closed or neutral position. Each end of the cylinder 16 has a small hole or leak valve 33 therein and the motive fluid which 110 has actuated the piston to move it toward either end will gradually exhaust, thus

allowing the corresponding compression spring 17 to return the piston 15 and the connected parts to neutral after the length of time which it is desired to display a signal has expired. It will of course be obvious that the rapidity of exhaust may be adjusted and regulated so that the signal may be displayed the desired length of time. If the desired turn had been to the right 10 the handle 25 would have been moved to the right and air admitted through the pipe 19 to the cylinder through the opposite end, the operation of the parts being relatively the same but in the opposite direction.

15 It will thus be evident that I have provided a signaling device for the use described which will automatically return to neutral without any manipulation on the part of the driver other than releasing the 20 valve handle 25 and that it therefore can not be carelessly left in signaling position —as from any wrong signaling accidents would be very liable to occur.

If desired a red or other colored transparent portion 34 may be provided in the casing for the purpose of providing additional means for calling attention to the indicator.

Having thus described my invention what

I claim and desire to secure by Letters Patent is:

30

1. In a device of the class described, indicating mechanism, a fluid pressure cylinder, means for supplying motive fluid thereto, a double acting piston in said cylinder, connections from said piston to said indicating mechanism for actuating the same in two directions, and means for returning said piston to intermediate position when said motive fluid has been cut off.

2. In a device of the class described, a casing having a transparent portion therein, an indicating drum revolvably mounted in said casing and carrying a plurality of directions thereon, a pinion mounted to revolve with said drum, a rack in operative relation to said pinion, a double acting piston rod connected to said rack, a piston on said rod, a cylinder in which said piston is adapted to reciprocate, springs tending normally to hold said piston centrally of said cylinder, and connections for supplying motive fluid to either end of said cylinder.

40 In testimony whereof I have hereunto affixed my signature.

BERT A. SEBRING.
